UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

CONDUIT PLOW.

Application filed July 5, 1922. Serial No. 573,033.

To all whom it may concern:

Be it known that I, WILLIAM SCHAAKE, a citizen of the United States, and a resident of Pittsburgh, in the county of Allegheny and State of Pennsylvania, have invented a new and useful Improvement in Conduit Plows, of which the following is a specification.

My invention relates to conduit plows or current collectors that are carried by a vehicle and engage conductors lying in a conduit adjacent to the path along which the vehicle travels.

The object of my invention is to provide a plow that is efficient in operation and embodies means for insuring against short circuits across a pair of conductors that are disposed within the plow.

Another object of my invention is the provision of a plow wherein those parts which are normally subject to damage may be removed and replaced as units, without the necessity of discarding the entire plow or any substantial portion thereof.

25 As shown in the accompanying drawings, Figure 1 is a view, in side elevation, of a conduit plow embodying my invention;

Fig. 2 is a view taken at right angles to that of Fig. 1;

30 Fig. 3 is a bottom plan view;

Fig. 4 is a detailed view of the main body portion of the plow with conductors imbedded therein;

Fig. 5 is a view taken at right angles to that of Fig. 4;

Fig. 6 is a detail view of one of the side members for attachment to the lower end of the body member of Fig. 4;

Fig. 7 is a detail view of one of the filler plates;

Fig. 8 is a detail view of the shoe supporting bracket, and

Figs. 9 and 10 are side elevational and end elevational views, respectively, on an enlarged scale, of the terminal blocks which I employ.

The apparatus comprises a body portion 12 of molded insulating material within which are imbedded conductor strips 13 and 14 that are bent outwardly, at their lower ends, in opposite directions, as shown more clearly in Figs. 4 and 5. The conductor strips 13 and 14, at their upper ends, are bent around conductors that lead to appa-

ratus within the vehicle, (not shown) as indicated in Fig. 1.

The upper, reduced, portion of the member 12 is protected from injury by metal side plates 15 and by filler plates 16 (Figs. 1 and 7). The filler plates 16 are disposed at opposite edges of the said reduced portion and serve to fill the spaces between the side plates 15 as well as to protect the edges of the member 12. The side plates 15 are cut away at points 17 and steel wearing plates 18 are riveted to the bars 16 at these points, the wearing plates 18 being thicker than the plates 15. The plates 18 are so positioned that they will engage the side walls of the conduit slot.

Whenever these plates become badly worn, they may be easily replaced without disturbing the other portions of the plow. They are relatively thick and protect the side plates 15 against excessive wear. The side plates 15 are riveted to the filler plates 16, as shown in Fig. 1.

Side members 19 and 20 of insulating material are secured to the lower end of the body member 12, by means of bolts 22 and 23, and are each provided with an opening 24 (Fig. 6) through which the lower ends of the conductors 13 and 14 may respectively extend.

The side members 19 and 20 are each provided with holes 25 that are recessed at their inner ends. Bolts 26 extend outwardly through the holes 25 and have their heads disposed within the said recesses so that their inner ends are flush with the inner surfaces of the members 19 and 20, to permit such members to lie flat against the body 12.

The bolts 26 extend through holes 27 of brackets 28, three of the bolts extending in one direction for connection to one of the brackets and the other three bolts extending in the other direction to support the other bracket 28 (Figs. 1 and 8).

Pins 29 extend outwardly through holes 31 in the brackets 28 and are provided with holes in their outer ends, as indicated more clearly in Figs. 1 and 2.

Cotter pins 32 extend through the holes in each pair of the pins 29, in order to hold the leaf-spring members 33 in place, as shown more clearly in Figs. 1 and 3. The ends of the springs 33 have lateral projections 34 that engage the sides of the pins to

prevent displacement of the springs. The ends of the springs 33 may slide somewhat upon their supports, in order that they may yield more readily under compression.

5 At their middle portions, the springs carry contact shoes 36 and 37 that engage conductors (not shown) within the conduit.

The shoe 36 is connected through a flexible shunt 38 to the lower end of the conductor strip 13, through a terminal block 39, the one end of the shunt 38 being secured to the shoe member, as shown more clearly in Fig. 3, and the other end thereof being secured to the terminal block 39 by screws 41 that extend into threaded holes 42 of the terminal block 39 (Figs. 1 and 9).

The lower end of the conductor strip 13 is secured to the terminal block 39 by screws 43 that engage the threaded openings 44 of the terminal block. The terminal block is secured to one of the brackets 28 by means of screws that extend through the holes 45 of the terminal block and into openings 46 of one of the brackets 28, the terminal blocks, as illustrated in Figs. 9 and 10, being shown on an enlarged scale. The shoe 37 is connected to the lower end of the conductor strip 14 through a flexible shunt 47 and a terminal block 48. The manner in which 30 this shunt is attached to the terminal block and the manner in which the terminal block is secured to one of the brackets 28 is the same as in the case of the shunt 38 and the terminal block 39 above described.

35 A pair of deflector bars 49 are supported by the bolts 22. These bars are so formed that they deflect moisture from the walls of the side plates 19 and 20, and thereby aid in keeping the moisture from entering crevices between such side walls and adjacent parts.

The shoes 36 and 37, by reason of their resilient mounting may readily accommodate themselves to irregularities in the conductors with which they co-operate. Should one of the shoes or its supporting members become damaged, it may be readily replaced without disturbing the other shoe. For instance, by removing the nuts from bolts 26 and the screws 43 from the terminal blocks, a shoe and its supporting members may be removed as a unit without disturbing any of the other portions of the apparatus. Or, by removing the cotter pins 32, and disconnecting the flexible shunt, the shoe and its supporting spring may be removed without disturbing the mounting of its supporting bracket 28. The examples here given are by way of illustration, and various other replacements may be made with equal facility.

I have, therefore, provided a conduit plow that is highly efficient in its operation and which subjects the user to but small loss in case of injury to one of the parts of the plow.

65 Furthermore, the device is of simple con-

struction and may be quickly assembled or disassembled.

Various changes in detail and general arrangement may be made without departing from the spirit and scope of the invention as defined in the accompanying claims.

I claim as my invention:

1. A conduit plow comprising, in combination, a body portion of insulating material within which a pair of conductors are imbedded, a detachable mounting secured to each side of the body member, a yielding support detachably secured to each mounting and a shoe detachably secured to each yielding support and having electrical connection with one of the said conductors, said mountings being insulated from said body portion and conductor members. 75

2. A conduit plow comprising, in combination, a body portion of molded insulating material, a plurality of conductor members imbedded therein, side plates of insulating material secured to the body portion, a bracket member secured to the side of each plate, a yielding member secured to the bracket members, and a shoe carried by each of the said yielding member, the shoe having electrical connection with said conductor members. 85

3. A conduit plow comprising, in combination, a body portion of molded insulating material, plates secured at opposite sides of the said body portion, a bracket secured to each plate, a yielding member supported by each bracket and a shoe supported by 95 each yielding member, each bracket being independently secured to its associated side plate. 100

4. A conduit plow comprising, in combination, a body portion of molded material 105 having conductor members imbedded therein, metal side plates for protecting the said body portion against injury, disposed at opposite sides thereof, filler plates disposed along the longitudinal edges of the said body portion, wear resisting blocks extending beyond the outer sides of the side plates, and means for securing the wearing blocks and the side plates to the filler plates. 110

5. The combination, in a conduit plow, of 115 a body portion of molded material having a pair of conductors imbedded therein, side members of insulating material secured to the body member at opposite sides thereof, a bracket detachably secured to each side member, a spring support detachably secured to each bracket member, a shoe secured to each of said supports, and a flexible electrical connection between each shoe and one of the said imbedded conductors. 120

In testimony whereof, I have hereunto subscribed my name this first day of July, 1922.

WILLIAM SCHAAKE.
